UNITED STATES PATENT OFFICE.

MARGARET C. R. FAIR, OF EAST CAMBRIDGE, MASSACHUSETTS.

INSTEP-SUPPORT.

1,086,358.

Specification of Letters Patent.

Patented Feb. 10, 1914.

Application filed November 11, 1908. Serial No. 462,090.

To all whom it may concern:

Be it known that I, MARGARET C. R. FAIR, a citizen of the United States, and a resident of East Cambridge, in the county of Middlesex and Commonwealth of Massachusetts, have invented certain new and useful Improvements in Instep-Supports, of which the following is a specification.

For the help of weak insteps or broken arches, it is customary to insert in the shoe a steel arch fixed to a suitably shaped piece of leather. Such steel arches are, however, so comparatively unyielding that they frequently injure rather than remedy the foot, and render the gait of the wearer stiff and stilted, and weaken the muscles of the feet through disuse.

The object of this invention is the construction of an arch or instep support which shall not be open to the recited defects, but will on the contrary, while fully supporting the instep, be pliable, resilient, self-adjusting, automatically giving support to the portion of the foot which needs it, and in addition possessing other advantages, such as a capability of being readily varied to fit the foot both when first worn and also as the foot increases in strength.

Referring to the drawings forming part of this specification, Figure 1 is a longitudinal section on the line Y—Y in Fig. 2 of an instep support made in accordance with my invention. Fig. 2 is a view of the support from beneath, before the exterior chamois under layer has been applied thereto. Fig. 3 is a cross section on the line X—X in Fig. 2. Fig. 4 is a face view of the reinforcing spring. Fig. 5 is an edge view of the same.

In the construction of this instep support, I first take a suitable strip of leather 1 shaped to fit the intermediate part of the shoe for which it is intended, and then give it the proper transverse and longitudinal curvatures indicated in Figs. 1 and 3; the same being substantially identical with the leather now customarily used in connection with steel arches. As soon as thus curved, what is to be the under surface of the leather is given a coating of shellac, as indicated by the stippling 2 in Fig. 2. A quantity of curled hair 3 is now applied to the leather arch 1, as indicated in Figs. 1 and 3, and confined in place by means of a square of fabric, preferably cotton cloth 4, either stitched at its edges to the arch 1, or held by said shellac, or by both the shellac and the stitches. Over

this fabric 4 is placed a sheet of pliable leather 5 strongly stitched at its edges to the arch 1 by one or more rows of stitches 6. Through this leather 5 are cut three slits; 60 one a substantial semi-circle near one end for the purpose of forming a movable flap 7 giving access to the space between said leather 5 and the fabric 4; and the other two slits being straight and parallel near the mid-length of the leather to form the neck 8. A leaf spring 10 formed of resilient metal, as thin steel well tempered, and normally arched as shown in Fig. 5, but otherwise shaped as illustrated in Fig. 4, is then inserted through the opening 11 formed by bending the flap 7 outward, and also exterior to the neck 8, to the position indicated by the dotted lines 12 in Fig. 2. An exterior layer of chamois skin 15 being pasted or 75 otherwise secured beneath the entire instep support, and itself formed with a flap 16 corresponding in location to that first described and also with an opening 17 for providing ventilation, the invention is complete. 80

In case the foot for which the instep support is desired is naturally quite flat, then the spring 10 will be withdrawn from place, given a slightly less pronounced curvature, and returned. If the foot is naturally a 85 high-arched one, then in the same manner the spring will be withdrawn, bent to a sharper curve, and returned. In the same way the spring can be adjusted to accommodate a flat foot at the beginning of the treatment, and afterward more strongly arched to fit the foot as it becomes stronger and nearly normal in shape. Said spring is made quite flexible and incapable of too strong local pressure against the arch of the 95 foot, so that it cannot produce a hurtful effect, while its resilience causes it to constantly maintain a yielding upward pressure where required. Its flexibility and resilience further permit of a portion of the 100 strain of supporting the instep being taken by the muscles of the foot, and so causes them to steadily acquire new strength, instead of weakening them still further by disuse. 105

The action of the curled hair 3 is to fill the space between the sole of the shoe and the arch of the foot therein, and by its cushioning action to properly support the instep. This supplements the spring 10, and by its 110 readjustment in position acts to accumulate at points where the foot most needs it; thus

rendering this instep support automatically adjusting. At the same time, this curled hair cushion does not interfere with the flexibility of the instep support, while its slight resilience provides a limited bellows effect which serves to give a circulation to the air within it. This air circulation is produced by the compression of the curled hair and the walls surrounding it, and the consequent expulsion of the air therein; the expulsion being permitted by the opening 11. Then as the pressure of the foot is taken off and the curled hair again expands its walls, air is drawn in to fill the vacancy. This circulation keeps the instep support dry, and at the same time reduces foot-perspiration.

The object of the leather sheet 5 is mainly to retain the spring 10 in place, the stitches 20 keeping the spring from longitudinal displacement, and the neck 8 holding it from lateral movement. The purpose of the chamois skin 15 is partially to conceal the other parts and so improve the appearance 25 of the article, but mainly to keep the instep support from slipping along the shoe sole; the rough unfinished surface of the chamois serving to accomplish this function. The instep support is also a more efficient article 30 even without the spring 10, the curled hair alone serving by its resilience and pliable action to provide the required support for the foot.

What I claim as my invention and for

which I desire Letters Patent is as follows, 35 to wit:—

1. An instep support comprising a pliable arch, a fibrous pad beneath the same, a leaf spring beneath said pad, and a sheet beneath said spring and pad and secured at its edges 40 to said arch, said sheet being formed with an opening for the removal and replacement of said spring.

2. An instep support comprising a pliable arch, a fibrous pad beneath the same, a leaf 45 spring beneath said pad, and a leather sheet beneath said spring and pad; said sheet having two parallel slits for the reception of the spring and an opening for its removal.

3. An instep support comprising a leather 50 arch, a quantity of curled hair beneath the same, fabric inclosing said curled hair, a leaf spring beneath said fabric, a sheet of leather secured to said arch below said spring and fabric and having an opening for the removal of 55 said spring, means for retaining the spring in position, and chamois skin secured to said arch beneath said sheet and formed with an opening for the removal of said spring. 60

In testimony that I claim the foregoing invention, I have hereunto set my hand this 6th day of November, 1908.

MARGARET C. R. FAIR.
